UNITED STATES PATENT OFFICE.

JOHN J. IVANCEVICH, OF PORTLAND, OREGON.

PROPELLER.

1,087,586.

Specification of Letters Patent.

Patented Feb. 17, 1914.

Application filed June 11, 1913. Serial No. 773,086.

To all whom it may concern:

Be it known that I, JOHN J. IVANCEVICH, a citizen of the United States, residing at Portland, in the county of Multnomah and 5 State of Oregon, have invented certain new and useful Improvements in Propellers, of which the following is a specification.

This invention relates to an improvement in propellers, and has for its object to provide a propeller for use in either water or 10 aerial navigation, but it is especially adapted for use in the air.

A further object is to provide a revolving motor which is so constructed that its wings 15 will offer a resistance to the medium in which they move while at one side of the point of revolution, and will swing so as to offer the least possible resistance while at the other side of that point.

20 These and other objects are accomplished by means which are illustrated in the accompanying drawing, in which—

Figure 1 is a plan view of the propeller when standing in a horizontal position on 25 its axis. Fig. 2 is a side elevation of same. Fig. 3 is a sectional view taken on the line A—A of Fig. 1. Fig. 4 is an end view showing the wings separated and presenting their edges toward the line of movement.

Describing the drawing in detail, 1 represents a pair of bars, spaced apart and pivoted at their median points to the sleeve 11 which is held between the collars 20 on the 30 fixed shaft 14. Toward each end of each arm or bar 1 is fixed at right angles thereto a pivot pin 3. These pins are disposed in pairs, and the pair at each end is at the opposite side of the bars with reference to the 35 other. Upon each of said pins is pivoted a bracket 4 carrying a rod 5, upon which is secured a metallic sheet 2, to which is secured at its outer edge another bar 5. From each lower bar 5 a pivot bar extends to and connects with the opposite upper bar 5, which 40 holds the bars 5 parallel to each other, which will permit the sheets to separate at their outer edges and to approach each other at their inner edges, by the separation of bars 45 1; and conversely, by the contraction of bars 1, the sheets will be brought to approximately parallel position and somewhat separated from each other. At a suitable point intermediate the central shaft and the termi- 50 minus of each bar 1 is pivoted upon pin 7 a toggle link 8 connected by means of pin 9

with the connecting rod 10 which is slidably mounted by means of the longitudinal loop 22 upon the shaft 14, between the shoulders 21. At the median portion each bar 1 is divided into upper and lower portions which are shaped to describe a circle 1^a, and in which are formed at right angles to the plane of the arms, the bearings 13 carrying the spindles 13 which are fixed in the sleeve 11. These spindles are sustained by the stay 12, which is circularly formed in conformity to the circular portion 1^a. Fixed upon the shaft 14 adjacent one end of sleeve 11 is a sprocket wheel 15 carrying a chain 16 engaged upon the similar sprocket 15^a fixed upon the shaft 17^a carried in a suitable bearing formed upon one of the stays 12 parallel with the main axle 14. Upon the inner end of shaft 17^a is fixed a crank 17 having a 60 wrist pin 23 which has a sliding bearing in the transverse slot 18 formed in the head of the connecting rod 10.

The shaft 14 being fixed, and power being applied to the pulley 19 secured upon the 65 sleeve 11, preferably at the end opposite from the sprocket wheels, the sleeve will be rotated, for example, in the direction indicated by the arrow. With each revolution of the arms 1 there will be one revolution 70 of the crank 17 causing the connecting rod to move through one cycle. As the connecting rod reaches the forward limit of its throw, as seen in Fig. 1, the arms will be 75 spread to their limit which will rock the arms 1 on the spindles 13, expanding the advancing ends and contracting the returning ends to the positions indicated at 1^b. This will cause the wings at one end to expand and gather the air while those at the 80 other end will present their edges to the air. By the rotation of crank 17 the pitman rod will be caused to reach the opposite limit of its throw at the moment the other ends of bars 1 reach the point in their revolution 85 described for the ends carrying the toggle links. This will retract the toggle links, and contract that end of the bars carrying them, which correspondingly expands the other ends. In this manner the wings are 90 made to expand and resist the air or medium through which they move in one half of their revolution, and to present their edges to the line of advancement in the other half of their revolution, thereby causing 95 a constant pressure against such medium, the force of which will react upon the ves-

sel carrying the propeller, to give it locomotion.

It is obvious that by reversing the direction of the power upon the pulley 19 a corresponding change in the direction of the vessel will be effected.

Having now described my invention, what I claim, is—

1. A propeller comprising a shaft, a sleeve 10 mounted thereon, bars pivoted at an intermediate point upon said sleeve, a pitman rod slidably mounted upon the sleeve between said bars, a toggle link connecting the free end of the pitman with each arm, wings 15 mounted to collapse and expand upon each end of the arms, and means for reciprocating said pitman to alternately contract and expand each end of the pair of bars.

2. A propeller comprising a shaft, a sleeve 20 mounted thereon, bars each having a looped central portion, a pivot member connecting the sleeve centrally in each looped portion, a pitman rod slidably mounted upon the sleeve between said bars, a toggle link connecting the free end of the pitman with each arm, wings 25 mounted to collapse and expand upon each end of the arms, a shaft mounted to bear in one of said pivot members, having a gear wheel fixed thereon, means oper- 30 atively connecting said gear wheel with the main shaft, and a crank fixed upon the second mentioned shaft having a wrist pin engaged in a transverse slot in the head of the pitman for alternately expanding and contracting the opposed members of said bars at each end.

3. A propeller comprising a shaft, a sleeve

mounted thereon, bars each having a looped central portion, a pivot member connecting the sleeve centrally in each looped portion, 40 a pitman rod slidably mounted upon the sleeve between said bars, a toggle link connecting the free end of the pitman with each arm, wings mounted to collapse and expand upon each end of the arms, a shaft mounted 45 to bear in one of said pivot members, having a gear wheel fixed thereon, means operatively connecting said gear wheel with the main shaft, and a crank fixed upon the second mentioned shaft having a wrist pin 50 engaged in a transverse slot in the head of the pitman, whereby the bars may be simultaneously expanded at one end and contracted at the other, at a given point in their revolution, and such movements will be reversed at one half revolution therefrom.

4. A propeller comprising a shaft, a sleeve mounted thereon, bars pivoted at an intermediate point upon said sleeve, a pitman rod slidably mounted upon the sleeve be- 60 tween said bars, a toggle link connecting the free end of the pitman with each arm, wings mounted to collapse and expand upon op- 65 posing faces at each end of each pair of arms, means for reciprocating said pitman to alternately contract and expand each end of the pair of bars, and means for preserving the wing supports parallel to each other.

In testimony whereof I affix my signature in the presence of two witnesses.

JOHN J. IVANCEVICH.
